UNITED STATES PATENT OFFICE.

JOSIAH B. GATHRIGHT, OF LOUISVILLE, KENTUCKY.

AUTOMATIC CAR-BRAKE.

SPECIFICATION forming part of Letters Patent No. 323,659, dated August 4, 1885.

Application filed December 19, 1884. (No model.)

To all whom it may concern:

Be it known that I, JOSIAH B. GATHRIGHT, a citizen of the United States, residing at Louisville, in the county of Jefferson and State 5 of Kentucky, have invented certain new and useful Improvements in Automatic Car-Brakes, of which the following is a specification, reference being had to the accompanying drawings.

10 The object of my invention is to so improve the ordinary hand-brake devices that they may be set at will, so as to act in connection with the automatic devices without impairing or interfering with their use as hand-brakes 15 at any moment.

It consists in certain simple additions to the hand-brake devices, which are fully described hereinafter.

In the drawings, Figure 1 represents the 20 under side of a car provided with a system of hand-brakes adapted to act upon the wheels of both trucks, and having added thereto my improved devices for transforming them into "automatic" brakes at will. Fig. 2 represents 25 a modification of the same applied to hand-brakes adapted to act upon the wheels of one truck only of a car.

In Fig. 1 the brake-wheels D and D, brake-stems d and d, chains No. 1, lever F, and chains 30 No. 3, with beams H and shoes h, illustrate a kind of hand-brake in common use, which acts upon both trucks, and is operative from either end of the car. To improve this system so that it will also work automatically when desired,

35 I interpose at some point between the brake-wheel D and the brake-shoes an elastic part or spring, as shown by G in the drawings, where it forms a part of chain No. 1, and I also add to the system chain No. 2, which

40 connects the sliding draw-bars B B with lever F, as shown. If, now, the hand-brakes are wound up and locked in the usual way, the brake-shoes will press upon the wheels with the usual force; but by reason of the elastic 45 section G the brake-beam and shoes may be released or forced away from the wheels without unwinding or unlocking the brake-stem. It will be seen that the sliding draw-bar B, acting through chain No. 2 upon lever F, per- 50 forms this function of relieving the brake-pressure whenever the draw-bar is drawn

out by the usual draft upon it necessary for starting and pulling the car; also that when the pull upon the draw-bar ceases, (as when stopping the train or going down grades,) the 55 elastic force of the wound-up hand-brakes will promptly apply the pressure to the wheels again.

It will thus be seen that the ordinary hand-brakes are rendered automatic when provided 60 with my improvements by simply winding them up and leaving them locked in that condition. It will be seen, also, that it will not only act promptly to stop the whole train whenever the engine ceases to pull it, because 65 there is no longer draft upon the draw-bars sufficient to hold the brakes off the wheels; but for the same reason it will act promptly to stop the rear section of a broken train, thus preventing many bad accidents. 70

For backing, yard-switching, &c., I would simply throw off the brakes (unwind the stems) and use them in the ordinary way. Any device with brakes of this class which will admit of backing (automatically) will be 75 almost sure to lead to a failure of the brakes to act at some critical moment. The action of one part of a train upon another is the same when backing as when checking up or stopping, and yet an automatic momentum- 80 brake would have to act in one case, and not act in the other. This gives too much chance for accidents; hence I prefer, as before said, to throw off the brakes for backing under my system. Even then my device saves more 85 than half the usual time and labor in backing, switching, &c., for when a train has been backed and the brakes have been wound up to stop it they need not be thrown off for starting forward, and will act automatically for stop- 90 ping the train again.

It is not necessary to point out in detail the application of my improvements to the changed conditions, (shown by Fig. 2,) as the drawings will be easily understood after what has 95 been already said above. Nor is it necessary to point out how my invention is applicable to any one of the many kinds of hand-brakes in use, for, the principle being clearly shown, it only requires a little mechanical skill to 100 adapt my invention to the different conditions which these different systems present. Hence

I do not wish to confine myself to the particular mechanisms shown in the drawings, and herein described.

I would remark that the brakemen under my system can wind the brakes more or less tightly, according as the cars may be empty or loaded, &c., and may increase or diminish the pressure according to the grades to be gone over.

10 What I claim as new, and desire to secure by Letters Patent, is—

An automatic car-brake consisting of an ordinary hand-winding shaft, and a winding-chain having a spring portion intermediate

between the winding-shaft and the end of a 15 pivoted brake-lever, thus rendering the winding-chain elastic or extendible, a chain connecting the opposite end of the brake-lever with the brake-beam, and the same end of the pivoted lever connected by chain with the 20 draw-bar, substantially in the manner and for the purposes specified.

In testimony whereof I affix my signature in presence of two witnesses.

JOSIAH B. GATHRIGHT.
